UNITED STATES PATENT OFFICE

137,676

DESIGN FOR AN ASTRONOMICAL GLOBE

George B. Eisler, New York, N. Y.

Application February 2, 1944, Serial No. 112,407

Term of patent 14 years

(Cl. D25—1)

To all whom it may concern:

Be it known that I, George B. Eisler, formerly a citizen of Germany and now stateless and residing at New York, in the county of New York and State of New York, have invented a new, original and ornamental Design for an Astronomical Globe, of which the following is a specification, reference being had to the accompanying drawing, forming part thereof, and in which the figure is a perspective view of an astronomical globe, showing my new design.

The dominant feature of my design resides in a transparent globe with a transparent diametrical ring bearing spherical representations not to scale, of the sun and various planets and satellites, the globe having representations of the fixed stars thereon, as shown.

I claim:

The ornamental design for an astronomical globe, substantially as shown and described.

GEORGE B. EISLER.
